US0D1017361S

(12) **United States Design Patent** (10) **Patent No.:** **US D1,017,361 S**
(45) **Date of Patent:** **** Mar. 12, 2024**

(54) **DRILL**

(71) Applicant: **BLACK & DECKER INC.**, New Britain, CT (US)
(72) Inventor: **Michael Cox**, Felton, PA (US)
(73) Assignee: **BLACK & DECKER INC.**, New Britain, CT (US)

(**) Term: **15 Years**

(21) Appl. No.: **29/782,401**

(22) Filed: **May 6, 2021**

(51) LOC (14) Cl. **08-05**

(52) U.S. Cl.

USPC **D8/68**

(74) Attorney, Agent, or Firm — Stephen R. Valancius

(57) **CLAIM**

The ornamental design for a drill, as shown and described.

DESCRIPTION

FIG. 1 is a perspective view of the drill.

FIG. 2 is a front view of the drill of FIG. 1.

FIG. 3 is a rear view of the drill of FIG. 1.

FIG. 4 is a left view of the drill of FIG. 1.

FIG. 5 is a right view of the drill of FIG. 1.

FIG. 6 is a top view of the drill of FIG. 1; and,

FIG. 7 is a bottom view of the drill of FIG. 1.

The broken lines depict portions of the drill and form no part of the claimed design.

1 Claim, 7 Drawing Sheets
